UNITED STATES PATENT OFFICE.

CARROLL E. DODSON, OF KANSAS CITY, MISSOURI, ASSIGNOR, BY MESNE ASSIGNMENTS, OF ONE-HALF TO UNION PHARMACAL COMPANY, A CORPORATION.

VANITY CASE.

Application filed July 5, 1922. Serial No. 572,767.

To all whom it may concern:

Be it known that I, CARROLL E. DODSON, a citizen of the United States, and resident of Kansas City, county of Jackson, State of Missouri, have invented a certain new and useful Improvement in Vanity Cases, of which the following is a complete specification.

This invention relates to vanity boxes or cases of that class adapted to be carried in a hand bag or the like, and has for its object the production of a device of the character named having a mirror and two cosmetic compartments susceptible of simultaneous exposure and accessibility for use.

A further object is to produce a device of this character of simple, compact, durable and inexpensive construction and attractive appearance.

With these objects in view, the invention consists in certain novel and useful features of construction and combinations of parts as hereinafter described and claimed; and in order that it may be fully understood, reference is to be had to the accompanying drawing, in which:—

Figure 1 is a perspective view of a vanity box embodying the invention;

Figure 2 is a perspective view of the vanity box in opened position;

Figure 3 is a vertical section taken through the vanity box in the plane of its hinges; and

Figure 4 is an enlarged horizontal section through the lower or bottom member of the box.

In the said drawing, 1, 2 and 3 represent the lower, intermediate and top members of the box, the member 1 forming the bottom and the member 3 the lid, and said members are hingedly connected by means of hinge plates 4 and 5, the former being secured to the member 1 by means of clamp hooks 6 extending through the wall of the member 45 as at 7. Hinge plate 5 is also provided with similar hooks 8 extending through openings 9 in the wall of the top or lid member 3, the relation between said members being such that the lid member is spaced from the bottom member and is adapted for swinging in a vertical plane.

The bottom member and the intermediate member are also hinged together so that the latter may be swung in a horizontal plane after the lid member has been raised

to open position, to expose the interior of the bottom member. Hinge members 10 are provided with clamp hooks 13 extending through openings 14 in the wall of member 1, and a similar hinge plate 11 is secured in the same manner to the wall of the intermediate member 2, a pivot pin 12 extending vertically through said hinge plates 10 and 11 to provide for the relative movement of said members above referred to.

The intermediate member is formed at its upper edge with a reduced portion 15 for fitting snugly in the lower edge of the wall of the top or lid member when the latter is closed, the parts being so proportioned that the exterior of the box as a whole shall be perfectly smooth and of uniform diameter except where the hinge plates occur, it being preferred to provide the reduced portion 15 of the intermediate member with a notch as at 16 for the accommodation of the enlarged or hinged points of hinge plates 4 and 5 to avoid any noticeable external projection of the box at such points, as shown by Figure 3.

For the purpose of holding the intermediate member upon and covering the bottom member when the former is not held in place by the lid or top member 3, the wall of the intermediate member is formed with a protuberance 17 for engagement with a cavity 18 formed in the inner face of hinge plate 4, there being a spring or yielding relation between the parts due to the character of the material permitting said protuberance and cavity to engage with a snap and hold with sufficient firmness to guard against accidental swinging movement of the intermediate member. The latter is also provided with an external protuberance 17^a for engagement with an internal cavity formed on the wall of the top or lid member, by pressing the said wall outward as at 18^a, so that when said lid is closed down upon the intermediate member, the engagement of said protuberance and cavity will serve to provide a spring catch for preventing accidental opening of the lid member.

The lower or bottom member 1 is provided with a horizontal partition 19 having depending marginal legs 20 to rest upon the bottom of said member, and said partition is provided with an opening 21 to form a chamber for holding a cake of rouge 22 and a rouge puff 23. It is also provided with

an opening 24 for holding a cake or stick for the treatment of the eye brows and lashes, such cake or stick being indicated at 25. It is also shown as provided with an 5 opening 26 to contain what is known as a lip stick, and with an opening 27 for receiving the bristle end of an eye brow and eye 10 lash brush 28. The particular form, character and number of the openings in the partition, however, are unimportant, as they 15 will be provided for the accommodation of the articles which it is deemed advisable shall be contained in the bottom member.

The intermediate member is adapted to 20 contain a large cake of powder as at 29 and a powder puff 30. Within the lid so as to be exposed when the same is raised, is a mirror 31, the same being shown as held in place by a retaining ring 32 fitted snugly 25 and frictionally within said lid.

From the above description it will be apparent that I have produced a vanity box or case embodying the features of advantage set forth as desirable in the statement of 25 the object of the invention, and which may be modified in some particulars within the spirit and scope of the appended claims.

I claim:

1. A vanity box comprising a bottom 30 member, a hinge plate projecting upward

from said member, a lid member having a hinge plate hinged to the first-named hinge plate and adapted for movement in a vertical plane, an intermediate member pivoted to the bottom member and adapted for horizontal swinging movement to expose the interior of said bottom member or to cover said member, and means for latching the intermediate member against accidental movement when forming a closure for the bottom 40 member. 35

2. A vanity box comprising a bottom member, a hinge plate projecting upward from said member, a lid member having a hinge plate hinged to the first-named hinge plate and adapted for movement in a vertical plane, and an intermediate member pivoted to the bottom member and adapted for horizontal swinging movement to expose the interior of said bottom member or to cover 45 said member; said first-named hinge member and the wall of the intermediate member having a cavity and a protuberance for engagement when the intermediate member is occupying a position upon and covering 50 the bottom member. 55

In witness whereof I hereunto affix my signature.

CARROLL E. DODSON.
